UNITED STATES PATENT OFFICE.

ROBERT E. JORDAN, OF CHICAGO, ILLINOIS.

HOG-DEHAIRING STRUCTURE.

1,270,239.

Specification of Letters Patent. Patented June 18, 1918.

Application filed July 13, 1917. Serial No. 180,465.

To all whom it may concern:

Be it known that I, ROBERT E. JORDAN, a citizen of the United States, residing at Chicago, in the county of Cook and State of Illinois, have invented certain new and useful Improvements in Hog-Dehairing Structures, of which the following is a specification, reference being had therein to the accompanying drawing.

10 This invention relates broadly to the treatment of animals, and specifically has reference to hog dehairing structures.

The object of the invention is to provide a structure in which the beater-elements are 15 disposed on a rotatable mounting so as to be hingedly connected thereto as distinguished from a rigid securement of the beater-elements to the mounting, whereby any tendency to develop a breaking strain 20 on the parts is minimized and the life of the structure prolonged.

A further object of the invention is to present an assembled structure, comprising a mounting and a series of beater-elements 25 hingedly connected thereto whereby such elements may have a swinging movement on axes which are parallel to the axis of the rotatable mounting to which they are attached; such swinging movement being in 30 relation to the mounting in order to obviate any tendency of the element to break at a particular point intermediate of its ends.

Still another and more specific object within the contemplation of the invention is 35 to provide a metallic mounting having radiating portions, to one of which is attached a reinforcing element of flexible material, preferably, and juxtaposed to which is a beater-element hingedly connected to the 40 mounting and normally maintained in an outstanding position by one of the radiating portions, the beater-element also being of flexible material, preferably.

Other objects and advantages of the invention will be seen to be inherent in the proposed structure, and still other objects and advantages will appear from the following description.

This invention seeks, in general, to provide 50 an animal-dehairing structure which is peculiarly adapted for use in dehairing and polishing hogs effectively and without injury to the carcass; this structure, from an operative standpoint, possessing a high degree of durability and efficiency, while yet 55 of great simplicity.

Drawings are hereto appended to illustrate some of the possible embodiments and utilizations of the invention; and it is to be understood that these embodiments and utilizations may be considerably varied, and that other possible embodiments and utilizations may be employed, all utilizing the underlying principles of the invention and falling within the spirit thereof and without 60 in the objects contemplated thereby. 65

In these drawings:

Figure 1 is a view in elevation, partly in section, of the beater-structure, one set of the beater-elements and reinforcing elements, carried thereby, appearing in dotted lines in the position they may assume as the beater-instrumentality is rotated;

Fig. 2 is a view in top plan of the same; Fig. 3 is a fragmentary view, in section, 75 on an enlarged scale, of a part of the mounting and the beater and reinforcing elements attached thereto;

Fig. 4 is a similar view showing the beater-element in its swung or operative position;

Fig. 5 is a fragmentary view of the hinge connection between the mounting and the beater-element;

Figs. 6 and 7 are fragmentary views in 80 end elevation and top plan showing a modified form of hinge connection between the beater-elements and the mounting; and

Figs. 8 and 9 are fragmentary views in end elevation showing other modifications.

In hog-dehairing and polishing machines, of present-day construction, the beater-elements are usually clamped rigidly in a mounting and, by reason of the fact that they rotate at the rate, say, of 165 revolutions per minute, these beater-elements upon coming into contact with the carcass tend to develop a hinge reaction at a point adjacent to that at which the elements are clamped, and the consequence is that these 100 elements will naturally break at that point and become useless in a comparatively short time; the manner of connecting the beater-elements, in my improved construction, efficiently obviates this danger.

In Figs. 1 to 5, I have illustrated a preferred embodiment of the invention as comprising a novel form of mounting and a novel means of securing the beater elements therein, as will now be described.

The mounting, designated generally by the reference-character 1, includes a set of

- aggrouped castings, each comprising a body-portion 2, a straight radiating portion 3, and a curved radiating portion 4. As seen in Fig. 1, these portions 3 and 4 are ag-
 5 grouped as companion portions, and are held in such relation by a bolt 5. By reason of the fact that these two portions are angu-
 lated in opposite directions with relation to the body-portion 2, there is provided be-
 10 tween them a space adapted to receive a set of beater and reinforcing elements, pres-
 ently to be described.
- The radiating portion 3 carries a hinge-
 web 6 through which extends a bolt 7.
- 15 Swinging on the bolt 7 and having its ends thereon, is a beater-clamping member 8, which is provided with prongs 9 which penetrate the lower portion of a beater-ele-
 ment 10.
- 20 Juxtaposed to the beater-element, and se-
 cured to the curved radiating portion 4, as by a bolt 11, is a reinforcing element 12.
- The beater and reinforcing elements are preferably formed of flexible material, such
 25 as rubber belting. The beater-elements, at their outer ends, carry hair-removing scrapers 13.
- As well seen in Fig. 3, the beater-element is so mounted on its axis 7 and in relation
 30 to the adjacent surface of the radiating portion 3 and of the reinforcing element 12 that there is a slight clearance or space between these surfaces to permit the beater-element to move on its axis 7 with respect to the
 35 radiating portions and the reinforcing element. By this construction, when the struc-
 ture is rotating—as in a clockwise direction—the resulting centrifugal action tends to swing each of the beater-elements on its re-
 40 spective axis; but this swinging movement is in part resisted by the reinforcing ele-
 ment 12 which, however, may bend and en-
 gage the inner surface of the curved por-
 tion 4, as shown in dotted lines in Fig. 1.
- 45 By this arrangement, a certain degree of freedom of movement of the elements 10 and 12 is permitted, the beater-element 10 swinging, as already mentioned, on its axis 7.
- 50 The axes are, thus, disposed parallel to the shaft 14 upon which the mounting 1 is secured. By reason of the swinging move-
 ment of the beater-element 10 on its axis, and the fact that it is not rigidly clamped
 55 in the mounting, this beater-element does not bend into an angular condition at any point, because this is precluded by the fact that it, in its entirety, swings on its axis; and there is in consequence no bending or
 60 straining point developed in the beater-
 element; wherefore the likelihood of break-
 ing or weakening of the beater-element inter-
 mediate of its ends is efficiently mini-
 mized, and there is, therefore, no hinge
 65 reaction produced on the element itself.

In Figs. 6 and 7, I have shown a modified form of hinge connection between the beater element and the axis 7; this modification involving a wire 15 or other appropriate instrumentality extended through the inner 70 end of the beater-element 10.

In Fig. 8 I have disclosed a modification of an entirely different character, this involving the hinging to a mounting 16 of a holder designated, generally, 17, and comprising a radiating straight portion 18 and a radiating curved portion 19 between which is disposed a beater-element 20 and a re-
 75 inforcing element 21 similar to the beater and reinforcing elements 10 and 12: In 80 this instance, the holding structure 17 is not integral with the mounting 16, as in the embodiment of Figs. 1 to 7; but it con-
 tempts connecting the holding structure to the mounting in such manner that the 85 former may have a slight swinging move-
 ment on the latter: To this end, the casting 16 is provided with extensions 22 and 23, suitably secured together and formed at their outer ends so as to present a head 24. 90 The head is adapted to be embraced by suit-
 ably formed portions 25 and 26, such that they may have a hinging movement on the head 24, such movement being limited by engagement of the lower ends 27 and 28, 95 respectively, of the portions 25 and 26 with the sides of the extensions 22 and 23, re-
 spectively. This arrangement provides for a slight swinging of the beater and reinforce-
 100 ing elements, and their holder, on the 100 mounting, it being understood that the beater-element 20, in this instance, may be of the construction illustrated in Fig. 3, for instance, or the manner of mounting the beater and reinforcing elements may be 105 similar to that disclosed in my co-pending application, Serial No. 152,423. This con-
 struction, of Fig. 8, is adapted to relieve any undue strains that may at any time be imposed upon the holding structure and 110 mounting when the beater element impinges against the carcass in performing its function of dehauling and polishing the same.

In Fig. 9, this feature of providing for movement between the holding structure 115 and the mounting is also embodied; but, in this instance, the mounting 29 carries embracing portions 30 adapted to hold the rounded ends 31 and 32 of radiating por-
 120 tions 33, and 34, respectively.

From the foregoing, it will be perceived that I have devised an efficient structure in which the tendency of impingement of the beater-element against a carcass to develop a bending and breaking point intermediate 125 of the ends of the beater-element is pre-
 vented; the hinging action between the beater-element and the mounting tending to permit a swinging movement of the beater-
 element on a defined axis and, thus, permit- 130

ting the beater-element to remain in a normally outstanding position without angular bending that would otherwise produce a breaking point.

5. What I claim is:

1. A beater structure including a mounting, a reinforcing element secured thereto and extending radially therefrom and having a swinging movement in respect to the mounting, and a flexible beater-element hingedly connected to the mounting and having a swinging movement in respect thereto and in relation to the reinforcing element and bendable beyond the limits of the mounting and against the reinforcing element.
2. As an article of manufacture, a beater structure including a mounting, a series of flexible reinforcing elements carried thereby and extending radially from the mounting and having a swinging movement in respect thereto beyond the limits thereof, and a series of flexible beater-elements hingedly connected to the mounting and having a swinging movement on their axes in respect to the mounting and a bending action in respect to the reinforcing element beyond the limits of the mounting.
3. As an article of manufacture, a mounting including radiating portions, a reinforcing element mounted on one of the portions and radiating from the mounting, and a flexible beater-element also radiating from the mounting, hingedly connected thereto, and having a bending action in respect to and against the reinforcing element.
4. As an article of manufacture, a beater structure including a mounting comprising

radiating portions, a reinforcing element connected to one of the portions and radiating from the mounting, a flexible beater-element normally arranged in substantial parallelism to the reinforcing element, and a hinge connection between the mounting and the beater-element.

5. As an article of manufacture, a beater structure including a mounting comprising radiating portions, a reinforcing element connected to one of the portions and radiating from the mounting, a flexible beater-element normally arranged in substantial parallelism to the reinforcing element, a hinge connection between the mounting and the beater-element, and an independent connection between the mounting and the reinforcing element.

6. A beater structure including a mounting comprising two spaced-apart radiating portions, a flexible beater-element radiating from the mounting and bendable adjacent the limits of the radiating portions, a hinge connection between the mounting and the beater-element to provide for a swinging movement of the element between the radiating portions, a reinforcing element also radiating from the mounting and likewise bendable adjacent the limits of the radiating portions thereof, and an independent connection between the mounting and the reinforcing element.

In testimony whereof I affix my signature in presence of two witnesses.
